P. LANCASTER.
IMPLEMENT FOR SHEARING SHEEP.

No. 12,760.

Patented Apr. 24, 1855.

UNITED STATES PATENT OFFICE.

PALMER LANCASTER, OF BURR OAK, MICHIGAN.

IMPLEMENT FOR SHEARING SHEEP.

Specification of Letters Patent No. 12,760, dated April 24, 1855.

To all whom it may concern:

Be it known that I, PALMER LANCASTER, of Burr Oak, in the county of St. Joseph and State of Michigan, have invented a new and Improved Implement for Shearing Sheep; and I do hereby declare that the following is a full, clear, and exact description of the same, reference being had to the annexed drawings, making a part of this specification, in which—

Figure 1, is a longitudinal section of my improvement. Fig. 2, is a plan or top view of ditto. Fig. 3, is a transverse section of ditto, (x) (x) Fig. 2, showing the plane of section.

Similar letters of reference indicate corresponding parts in the several figures.

The nature of my invention consists in the peculiar construction of the implement as will be hereafter shown and described, whereby the operation of sheep shearing may be performed in a perfect and expeditious manner.

To enable others skilled in the art to make and use my invention, I will proceed to describe its construction and operation.

A, A, represent two metallic plates secured a short distance apart by bolts or rods (a) as shown in Figs. 1 and 2. These plates may be of rectangular or other proper form.

On the upper surface of the upper plate A, there is a sliding frame B which works between suitable guides (b). The sliding frame is provided with an upright handle C. At each side of the frame B, there is attached a rack D, D', the rack D' being somewhat higher or projecting further up from the frame B, than the rack D, as clearly shown in Fig. 3.

E, represents a vertical shaft which works between the two plates A, A. The upper end of this shaft extends a short distance above the upper plate A, and has two pinions F, F', placed loosely upon it, one pinion being directly over the other. There are also on the shaft E two ratchets (c) (c') permanently attached to the shaft, the ratchet (c) being above the pinion F, and the ratchet (c') below the pinion F'. To each of the pinions F, F', there is secured a pawl (d) the ends of which are kept against the teeth of the ratchet by springs (e).

The rack D', gears into the upper pinion

F, and the rack D, on the opposite side of 55 the frame B gears into the pinion F'.

On the shaft E and between the two plates A, A, there is attached a spur wheel G, which gears into a pinion H, having a crank pulley I above it on the same axis 60 or shaft. To the crank pulley there is attached a connecting rod J, the outer end of which is secured to an arm K of a series of cutters (f) which work on a pivot (g), the cutters (f) being of saw tooth form and 65 attached to a common plate L, through which the pivot (g) passes, see Figs. 1 and 2.

The cutters (f) are directly over a series of stationary cutters (h) which are formed at the end of a plate M attached to the front 70 end of the lower plate A. The cutters (h) are of the same form as the cutters (f) but are inclined a little upward as shown in Fig. 1. The cutters (f) are very slightly inclined.

To the back end of the lower plate A there is attached a handle N having a bow O, at its end. The bow O is placed under the shoulder of the operator, and may if necessary be secured thereto by straps. The implement is placed upon the body of the sheep and the handle C is grasped by the right hand and moved back and forth, and a continuous rotary motion is given the spur wheel G in consequence of the pinions F, F' 85 only being connected to the shaft E when turned in one direction, viz, from left to right. This is effected by the pawls (d) (d'). As the spur wheel G gears into the pinion H a vibratory motion is given the 90 cutters (f) by means of the connecting rod K, and the cutters (f) work over the cutters (h) similar to the blades of shears, and will cut the wool from the animal in a perfect and expeditious manner, the implement of course as it cuts being moved over the body of the animal.

The advantage of this invention besides the rapidity, with which it operates is, that the implement will not mince or cut the wool 100 twice, nor cut the animal as is often done with the ordinary sheep shears.

Having thus described my invention, what I claim as new and desire to secure by Letters Patent, is,

The construction of the implement as herein shown and described, viz, having a series of cutters (f) work over a series

of stationary cutters (h), the cutters (f) having a vibratory movement given them by means of the reciprocating frame B, racks D, D', pinions F, F', with pawls 5 (d) (d) attached to them, and spur wheel G, pinion H and crank pulley I, the pinions F, F', being placed loosely on the shaft E of the spur wheel G, the above parts being arranged as shown and operating in the manner and for the purpose as set forth.

PALMER LANCASTER.
